H. Brockman

UNITED STATES PATENT OFFICE.

LOUIS STEINBERGER, OF BROOKLYN, NEW YORK.

SYSTEM OF LINE INSULATION AND INSULATORS THEREFOR.

Application filed June 27, 1921. Serial No. 480,503.

The main object of my invention is to so construct a line insulator and so install a system of line insulation as to provide an insulating structure by means of which conductors operating at vary high frequencies and voltages may be suitably supported, the insulators being of such design as to utilize to its full insulating value the air of the surrounding atmosphere.

Another object of my invention is to provide insulating supports for electrical conductors which for a given voltage may be of minimum practical dimensions and of maximum economy of construction, so that a given size insulator may be capable of withstanding higher voltages than insulators of substantially the same size but of other forms of construction.

Another object is to provide a construction of line insulators by means of which the arc is diverted to ground when a flash-over due to a current surge occurs.

Another object is to provide a construction of line insulator in which an electrode separated by air insulation from ground is connected directly to the line, which latter is supported by a solid dielectric.

Other objects will appear from the subjoined specification and claims.

The ability of any particular insulating device to withstand the electrostatic strains is known to depend far more on the distribution of the electrostatic strains and stresses in the dielectric or insulating material than on the thickness or amount of the said dielectric or insulating material, and I have taken advantage of this principle in producing my invention.

The insulators are so designed that each one used in the system of insulation will substantially preclude the concentration of electro-static lines of force thereupon and the bodies of air interposed between the metallic elements to be insulated one from the other, are utilized to their full insulating strength, thereby permitting a very economical construction.

In my insulating structure, therefore, I use a small amount only of solid insulating material and a minimum amount of conducting or metallic material, but the insulating and conducting or metallic members are so formed and interrelated as to make it possible to utilize the maximum insulation value of the air.

Referring to the drawings in which the

same reference character indicates the same part in the several views:

Fig. 1 is a vertical section, partly in elevation, of one of my improved line supporting insulators used in my new system of installation.

Fig. 2 is a plan of the supporting ring upon which the insulators are to be mounted in suitable position.

Fig. 3 is a view showing a plurality of insulators suitably installed.

In the drawings, the insulating unit consists of the body A of insulating material of hollow dome-shaped construction having an upper portion B and a serrated outer surface C, the space S being provided in the under side to form a suitable air insulation.

The mechanical construction is simple and it consists of a supporting stress distributing ring R having two upwardly extending flanges 10 and 11 and a downwardly extending thickened flange 12. The space 15 between the upwardly extending flanges serving as a groove within which the lower or base portion D of the insulator body fits and into which it is secured either by molding the body of insulating material thereto, as shown, when the insulating body is made of moldable insulating material such as Electrose. This structure may be adapted to support a flange base in the event that the insulating body is made of porcelain, or other similar insulating material, all as well known in the art.

A fitting 20, such as shown, is embedded in the upper bridge portion of the insulator body and extends therethrough, said fitting being flanged as shown so that it may be rigidly anchored in the insulating material. This fitting is provided with a protecting flange 21 extending radially therefrom which protects the upper portion of the insulator body and it is also provided with a screw-threaded extension 22 which projects upwardly and centrally thereof and a screw-threaded cavity 23 extending upwardly from the under side toward the center and also situated centrally thereof.

A washer W is placed over the projection 22 and has a screwthreaded hole so that it may be readily turned down into place. The line supporting element F is provided with a screwthreaded opening so that it may fit over the projection 22 and be screwed down into place against the washer W. This element F is provided with a groove g for the reception of the line wire L, as shown, and a circum-

ferential groove g^2 for the reception of the tie wire, as well known.

I also provide a metal hood 50 preferably of aluminum provided with an enlarged edge 51, said hood having a hole centrally thereof which is fitted in place over the projection 22 and the hood is thus held in place when the line supporting element F is secured down into closed position. This hood is effective 10 as an air gap electrode and stress distributor, and it also protects the insulator body from the elements of the weather in a manner well understood.

The ring shaped element R is provided 15 with a stress distributing surface R' which is adjacent to the electrode C' which latter is secured into place by means of its screw-threaded end engaging with the screwthreaded cavity 23 in the fitting 20.

20 The globular element G is fitted to the lower end of the electrode C' and is screwthreaded by means of a screwthreaded cavity in the element G, the walls of which engage with the screwthreads of the downwardly projecting 25 end of the electrode C'. The globular element G is designed to be at a greater distance from the ring shaped stress distributing element R than the distance of the surface R' of the said supporting ring, is from the electrode C', so that the arcing will occur between the surface R' and the centrally disposed electrode C'.

30 The insulator is mounted at any convenient place on suitably constructed cross arms or supports T by means of a specially designed metallic plate M which is circular in shape as shown, at one point of which extends a radial projection N extending from the sides of which are arms 60 and 61 each of 40 which arms has grooves or sockets a and b for the reception of staples 70, as shown, the arms or legs of the supports fitting into the notches a and b, as well understood.

45 When the arms 60 and 61 are used to be clamped by the staple, the insulator will be supported at right angles to the cross arms or support T whereas when the main projecting portion N is placed parallel with the support T the insulator is supported at the end of the 50 support in line therewith, and may be thus secured thereto.

55 The ring shaped portion of the supporting plate M is provided with a series of bolt holes o through which the supporting ring R of the insulator structure is secured by bolts, as shown. At the point where the ring support is immediately above the cross arm a holding screw or bolt 75 may pass through both the flange of the ring R and the plate M and extend 60 down into the support T in order to assist in holding the structure in position.

I have found by actual test that by the installation of such a structure as has just been described in place of the ordinary supporting 65 and insulating pins in a system of line insu-

lation, that great and beneficent results will follow. When the line is in operation, the insulation is accomplished through the air of the surrounding atmosphere and in the event of a surge coming over the line a discharge will take place between the electrode C' and the surface R' of the ring R, which will thus pass to ground, which results in a saving of the insulator and permits the formation of a structure in which a minimum amount of insulating material may be used and which in its entirety is thus capable of very high dielectric qualities.

70 As will be seen, by means of the location of the stress distributing element G on the electrode C' in juxtaposition to the metallic stress distributing element R' of the metal ring R, I have provided means for limiting the current below the insulator, said means being situated at a greater distance than the 75 length of the horizontal arc gap between the electrode C' and the stress distributing surface R'.

80 As changes of construction could be made within the scope of my invention it is intended that all matter contained in the above description or shown in the accompanying drawing shall be interpreted as illustrative and not in a limiting sense.

85 Having now described my invention, what I claim as new and desire to secure by Letters Patent is:

1. In a high tension system of the type described, a plurality of insulators, individual insulators of said system comprising the following: a metallic supporting ring connected to ground, a dome-shaped insulator supported on said ring, a metallic conductor supporting fitting secured to said insulator, and an electrode connected to said fitting and depending within said insulator and supporting ring to form an air gap with said supporting ring.

100 2. In a system for supporting a high tension transmission conductor, an insulator having an inner air chamber formed therein, a metallic line supporting fitting secured to said insulator, an electrode connected to said fitting and projecting through the air chamber in the insulator and a supporting ring for the insulator surrounding said electrode but spaced away therefrom to form an air gap and arranged to co-act with the electrode to direct the current to ground when abnormal surges 105 flow over the conductor.

110 3. In a system for supporting a high tension transmission conductor, an insulator having an inner air chamber formed therein, a metallic line supporting fitting secured to said insulator, an electrode connected to said fitting and projecting through the air chamber in the insulator, a stress distributing hood secured to the fitting and a supporting ring for the insulator connected to ground and surrounding said electrode but spaced away 115 120 125 130

therefrom to form an air gap and arranged to co-act with both the electrode and the stress distributing hood when abnormal surges flow over the conductor.

- 5 4. In a system for supporting a high tension transmission conductor, an insulator having an air chamber formed therein, a stress distributing supporting ring for the insulator, an electrode extending through the air chamber in the insulator and through the stress distributing supporting ring, and means electrically connected with the electrode for supporting the conductor.
- 10 5. In a system of line insulation comprising a plurality of dome-type insulators, grounded ring-shaped stress distributors, means for supporting the base of each insulator upon one of said ring-shaped stress distributors, means for securing a power conductor to said insulators, and an electrode connected to said power conductor and extending through said ring to distribute the stresses

between the conductor and said grounded ring-shaped stress distributors.

6. In a system of insulation comprising a plurality of dome type insulators, a conductor secured to said insulators and a grounded ring shaped electrode secured to each insulator body, an electrode secured to the conductor and situated in juxtaposition to the ring-shaped electrode.

7. In a system of insulation comprising a plurality of dome type insulators each supported by a ring-shaped electrode, a conductor secured to said insulators, an electrode mounted on each end of a rod extending through each ring-shaped electrode and connected to the line forming an air gap with the ring-shaped supporting electrode.

In witness whereof, I have hereunto set my hand at the borough of Manhattan, city and State of New York, this 25th day of June, 1921.

LOUIS STEINBERGER.
